US00D440568S

(12) **United States Design Patent** (10) Patent No.: **US D440,568 S**
Rozenberg (45) Date of Patent: ** Apr. 17, 2001

(54) **INDEX FINGER BIOMETRIC APERTURE FOR A MOUSE**

5,335,278 8/1994 Matchett et al. .
5,335,288 8/1994 Faulkner .

(75) Inventor: **Roman Rozenberg**, Forest Hills, NY (US)

(List continued on next page.)

(73) Assignee: **Biolink Technologies International, Inc.**, Miramar, FL (US)

FOREIGN PATENT DOCUMENTS

(**) Term: **14 Years**

WO 98/11478 3/1998 (WO) .
WO 98/11501 3/1998 (WO) .

(21) Appl. No.: **29/118,204**

Primary Examiner—M. H. Tung

(22) Filed: **Feb. 4, 2000**

(74) Attorney, Agent, or Firm—Malloy & Malloy, P.A.

(51) LOC (7) Cl. **14-02**

(57) **CLAIM**

(52) U.S. Cl. **D14/402**

The ornamental design for an index finger biometric aperture for a mouse, as shown and described.

(58) **Field of Search** .... D14/402-10; D13/158; D21/324-33; 200/5 R, 5 A, 6 R, 6 A; 273/148 B; 345/156-67; 74/471 XY; 463/36-47; 382/124-7; 340/825.69, 825.7, 825.71, 825.72; 380/23; 455/4.1, 4.2, 352, 353; 348/161

DESCRIPTION

(56) **References Cited**

FIG. 1 is a top view of the index finger biometric aperture; FIG. 2 is a left side view thereof;

FIG. 4 is a right side view thereof;

FIG. 5 is a rear view thereof;

FIG. 6 is a bottom view thereof;

FIG. 7 is a top view of a second embodiment of the index finger biometric aperture;

FIG. 8 is a left side view thereof;

FIG. 9 is a front view thereof;

FIG. 10 is a right side view thereof;

FIG. 11 is a rear view thereof;

FIG. 12 is a bottom view thereof;

FIG. 13 is a top view of a third embodiment of the index finger biometric aperture;

FIG. 14 is a left side view thereof;

FIG. 15 is a front view thereof;

FIG. 16 is a right side view thereof;

FIG. 17 is a rear view thereof; and,

FIG. 18 is a bottom view thereof.

The broken line drawing of a mouse in all views is for illustrative purposes only and forms no part of the claimed design.
